UNITED STATES PATENT OFFICE.

JAMES DAY, OF SAN FRANCISCO, CALIFORNIA.

QUARTZ-MILL.

SPECIFICATION forming part of Letters Patent No. 254,805, dated March 14, 1882.

Application filed July 18, 1881. (No model.)

To all whom it may concern:

Be it known that I, JAMES DAY, of the city and county of San Francisco, State of California, have invented an Improvement in Quartz-
5 Mills; and I hereby declare the following to be a full, clear, and exact description thereof.

My invention relates to quartz-mills or ore-
stamps, the object of which is to increase the
force of stroke of the stamp without adding
10 more weight thereto.

My invention consists in the following con-
struction and arrangement of parts, whereby
the object of my invention is attained, and
which will be first fully described, and the points
15 of novelty set forth in the claim. All of this
will be fully seen in the course of the following
description, and by reference to the accompany-
ing drawings, in which—

Figure 1 shows front elevation of the stamp-
mill. Fig. 2 shows an elevation of the same.
Fig. 3 shows a vertical section of same. Fig.
4 shows details.

A represents an ordinary mortar, in which the
ore is placed, and B the stamp, with its stem
25 C guided and supported by the frame D, all
in the usual manner.

E represents the tappet upon the stem, and
F the cam, which is revolved by appropriate
power, and which is adapted to impinge against
30 the tappet and raise the stem and stamp, and
to release said tappet, so that the stamp may
drop upon the ore in the mortar below.

To the top of the frame D are bolted or other-
wise secured brackets I, to which is bolted
35 the cylinder G. In this cylinder is the piston
H, in this case being shown as an ordinary
pump-piston. It is well packed within the cyl-
inder by cup-leather, kept moist and soft by oil
or glycerine.

40 The top of the cylinder is open to expose the
top of the piston to the atmosphere. It is ob-
vious, however, that any other form of piston
or packing may be used which is suitable to
create a vacuum within the cylinder. To the
45 top of the piston or to its rod is secured by nut,
as shown, a cross-head, J, extending across the

cylinder and projecting on both sides. In its
ends are fitted rods or bars K K, the ends of
which are secured thereto by nuts. These rods
extend downwardly through appropriate guide
50 notches or grooves in the cylinder-base and
brackets, and are provided with a cross-piece,
L, to which their ends are secured by nuts.
This cross-piece or follower is so placed that
the top of the stem C, when raised by the cam,
55 will impinge against it and raise it up. In
doing this it raises the piston and creates a
vacuum in the cylinder. When the cam re-
leases the stem the pressure of the atmosphere
will drive the piston home, and the cross-base
60 L, striking the top of the stem, will give the
stamp a momentum much greater than it would
have if allowed to fall by its own weight. This
additional force is a matter of advantage, be-
cause I am enabled to use lighter stamps and
65 still have as much force in their stroke. Al-
though I have here shown the device as being
connected with an ordinary ore-stamp battery,
it is obvious that the same principle and de-
vice may be applied to any form of quartz-
70 mill or other mills whose object is to crush
material by the action of stamps or beaters.

The principle is to provide practical means
for increasing the blow of the beater, and this
object is obtained by the mechanism herein
75 shown.

Having thus described my invention, what I
claim as new, and desire to secure by Letters
Patent, is—

In a crushing-mill, a stamp or beater and
mechanism for raising and dropping the same,
in combination with the cylinder G, air-tight
piston H, and sliding frame consisting of the
cross-head J, cross-base L, and side bars or
rods, K K, arranged for operation substantially
85 as set forth.

In witness whereof I have hereunto set my
hand.

JAMES DAY.
